UNITED STATES PATENT OFFICE.

HENRY MONFORD SMITH, OF LYNDONVILLE, VERMONT.

DIMMING APPARATUS FOR HEADLIGHTS.

1,386,968.

Specification of Letters Patent. Patented Aug. 9, 1921.

Application filed November 17, 1919. Serial No. 338,555.

To all whom it may concern:

Be it known that I, HENRY MONFORD SMITH, a citizen of the United States, and a resident of Lyndonville, in the county of 5 Caledonia and State of Vermont, have invented an Improvement in Dimming Apparatus for Headlights, of which the following description, in connection with the accompanying description, in connection with the accompanying drawings, is a specification, 10 like characters on the drawings representing like parts.

This invention relates to dimming apparatus for lamps in general, and more particularly for headlights of motor vehicles.

15 The invention and its aims and objects will be best understood from the following description, taken in connection with the accompanying drawing of one illustrative embodiment of the invention, the invention in 20 its true scope being pointed out in the appended claims.

In the drawings:

Figure 1 is a vertical central section of a 25 headlight of motor vehicles, embodying one embodiment of the invention, with the operating switch and electrical connections shown diagrammatically;

Fig. 2 is a front view of the electric bulb and shades to coöperate therewith;

30 Fig. 3 is a top plan view of the upper shade and mounting thereof;

Fig. 4 is a front view of a part of the shade-operating mechanism and mounting thereof;

35 Fig. 5 is a representation, in part diagrammatic, of the shade-actuating means.

The invention is herein shown in its application to headlights for motor vehicles. Referring to the drawings, Fig. 1 shows a 40 headlight of well-known construction, having the usual casing 2 and lens 4. Within the casing 2 is a substantially parabolic partition 6, having a central opening surrounded by a sleeve 8 preferably integral 45 with said partition, the front surface of said partition 6 constituting a reflector 9 of usual construction. Within said sleeve 8 is mounted an electric bulb-socket 10 of usual construction, adapted to receive at its 50 forward end an electric light bulb 12, and having the usual contact or contacts (not shown) for the latter, adapted to be connected to a storage battery or other suitable source of electric current by wires 14, 14. 55 In the illustrative embodiment of the invention herein shown the dimming means

preferably comprises two curved shades 16 and 18 pivotally mounted at their rear ends upon the studs 20 and 22, respectively, said studs being carried upon opposite sides of 60 a band 24 (see Fig. 3) encircling the bulb socket 10 adjacent its forward end (Fig. 1), and clamped thereto by a clamping screw 26 and nut 28. Surrounding the stud 20, and secured to the rearwardly projecting shank 65 30 of the shade 16, is a pinion 32, and surrounding the stud 22, and secured to the rearwardly projecting shank of the shade 18, is a pinion 34. The pinion 32 meshes at its lower edge with a rack 36 shown in dotted 70 lines in Fig. 1 and in full lines in Fig. 4, while at its upper edge the pinion 34 meshes with a rack 38 (see Figs. 1 and 4).

From the construction described it will be apparent that, if the racks 36 and 38 be 75 moved in the direction of the lens (Fig. 1), the shades 16 and 18 will, through the connections described, be swung about their pivots into the positions shown in full lines in Fig. 1, thus dimming the light by cutting off a portion of the rays emanating 80 from the bulb 12, while, if said racks be moved in the opposite direction, said shades will be swung outwardly from each other into the positions shown in dotted lines 85 in Fig. 1, to obtain the full illuminating capacity of the light.

The shades will preferably be curved longitudinally and transversely in substantial correspondence to the curvature of the reflector 9, and their inner surfaces will preferably be provided with a reflecting surface, so that, when in the position shown in dotted lines in Fig. 1, they may take the place of the portions of the reflector surface 90 masked by them in that position and not materially impair the reflection of the light-rays.

My invention contemplates the provision of suitable means to operate the shades. I 100 may provide any suitable means for that purpose, but I preferably use means operated by electrical energy. As one convenient and simple form of such means I have here provided a solenoid 40 diagrammatically represented in Fig. 5, which may be of any well-known and usual construction. Herein said solenoid is contained within a casing 42, Fig. 1, removably secured to the bulb socket 10 by bands 44, 44, encircling 105 said socket and casing and having their free ends fastened together by screw-bolts 110

46, 46. One end of the core 48 of the solenoid projects from the front end of the casing 42 and is secured in any suitable manner to a curved bar 50 carrying the racks 36, 38, preferably formed integral therewith. The front end of the core 48 is preferably screw-threaded and extends through an opening in said bar, to which it is secured by a nut 52 screwed thereon.

10 The core 48 is provided with an intermediate sector 54 of insulating material, and at either side of the latter it is surrounded by the coils 56 and 58, respectively. If the coil 58 be energized, the coil 56 being de-energized, the core will be drawn to the right, Fig. 5, substantially from the dotted line to the full line position, while if said coil 56 be energized, the coil 58 being de-energized, the core will be drawn substantially from the full line position, Fig. 5, to the dotted line position in said figure. In the first instance the racks will turn the pinions so as to close the shades; in the second instance they will be moved to turn the pinions to open the shades. For energizing the coils I may use any suitable source of electrical energy. For convenience I preferably use a battery, which may be the regular storage battery of the automobile, and to which the coils are connected by suitable wiring, suitable means, such as a switch being provided to establish the necessary connection. In Fig. 1 I have diagrammatically represented a battery at 60, a switch at 62, contacts at 64, 66, and suitable circuits for connecting the coils to the battery. One circuit runs from the contact 64 through a wire *a* to one terminal of the coil 56, from the other terminal of the latter through wires *b* and *c* to one pole of the battery, and from the other pole of the battery through the wire *f* to the switch 62. The other circuit runs from the contact 66 through the wire *d* to one terminal of the coil 58 and from the other terminal of the latter, through wires *e* and *c* to one pole of the battery and from the other pole of the latter, through the wire *f* to the switch 62. It will thus be seen that with the switch 50 in contact with the contact 64, the coil 56 will be energized, while with the switch in contact with the contact 66, the coil 58 will be energized. With the switch in the intermediate neutral position indicated at 68 neither coil will be energized.

It will be found preferable to keep the switch in contact with the contacts 64 or 66, respectively, only so long as may be necessary to move the shades into or out of dimming position, and then to move said switch back to neutral position 68. In this way the battery will be called on only for the time required to move the shades into or out of dimming position, and electric energy will not be used up unnecessarily.

The shades will remain in dimming or undimming position indefinitely when once moved into these positions by the solenoid, without keeping the latter energized.

The main object of dimming devices is to 70 eliminate the inconvenience caused to pedestrians or drivers coming in the opposite direction, by the blinding glare produced by the undimmed headlights.

The blinding glare is due to the rays that 75 are reflected from the reflector 9, those reflected from the upper and lower surfaces of the reflector being particularly obnoxious in this respect. The unreflected rays emanating from the bulb do not have the blinding 80 effect, and those reflected laterally have it only to a lesser degree, if at all. From an examination of Fig. 1 it will be seen that the rays that would be reflected from the upper and lower surfaces fall substantially 85 within the angles formed by the lines *x*—*x* and *y*—*y*, and it will be noted that when the shades are in dimming position these rays are interrupted by the shades and are not reflected.

In the embodiment of the invention herein shown the shades are cut away more or less, as shown at 70, at either side, to allow more or less of the rays directed laterally to be reflected from the lateral surface of the reflector and to be projected from the headlight when the shades are in dimming position, should it be desired to have more light, than would be afforded by the unreflected rays alone, when the shades are in dimming 100 position, these laterally reflected rays being, as stated, only slightly objectionable, if at all. These cut-away portions 70 can, however, be omitted from the shades if desired, so as to cut off practically all of the reflected rays, and leaving only the unreflected rays when the shades are in dimming position.

In the embodiment of the invention herein shown, the throw of the two shades is 110 the same, but it will be apparent that, by varying the initial adjustment of the two shades and their pinions relatively to the racks, a different throw may be imparted to the two shades, with a corresponding variation in the dimming action.

I preferably make the shades and also the racks and pinions of some light material, such as aluminum or an aluminum or other light alloy so as to reduce the energy required for their operation as much as possible. They may be, however, made of any suitable material.

While I have herein, for the sake of simplicity, shown a single headlight equipped with the illustrative embodiment of my invention, it will be apparent that any reasonable number of lamps or headlights thus equipped may be operated as described from a single or a plurality of switches, in ac- 125 130

cordance with my invention, by providing the suitable connections, which latter and the mode and manner of making the same will readily suggest themselves to those skilled in the art. The switch may be placed in any suitable position, preferably on the dash-board of the automobile where it can be easily reached by the driver.

It will be obvious that various changes may be made in the details of the means herein shown for carrying the invention into practical effect, and it is to be understood that applicant does not regard himself as restricted or limited to these details, his invention in its true scope being definitely set forth in the claims.

Claims:

1. In a headlight or other lamp in combination, an electric bulb as a source of light; a reflector; opposed dimming shades movable to and from dimming position; and operating means to move said shades in substantially vertical direction to and from dimming position, said shades being oppositely curved transversely of said bulb and cut away laterally thereof so as to leave said bulb uncovered in front and at a portion of the sides thereof, while covering said bulb at top and bottom, when said shades are in dimming position.

2. In a headlight or other lamp, a source of light, a reflector, oppositely movable shades for said source of light between the latter and said reflector, and operating means oppositely to move said shades to

open and close the same, said shades being shaped, so that, when in closed position, they intercept rays directed upwardly and downwardly from said source of light and allow lateral and forward rays to pass freely.

40

3. In a headlight or other lamp, in combination, a source of light; a reflector; opposed dimming members between said reflector and said source of light; and operating mechanism for said dimming members, comprising racks within said headlight and pinions operatively connected to said dimming members and said racks, said racks facing in opposite directions.

45

4. In a headlight or other lamp, in combination, a source of light; a reflector; dimming members mounted for rocking movement between said reflector and opposite sides of said source of light; pinions carried by said dimming members; racks to co-operate with said pinions upon opposed sides thereof respectively; and electrically actuated operating means for said racks.

50

5. In a headlight or other lamp, in combination, a source of light; a reflector; dimming members between said reflector and opposite sides of said source of light; pinions carried by said dimming members; a rack member having rack teeth facing in opposite directions to co-operate with said pinions; and means to actuate said rack member.

60

In testimony whereof, I have signed my name to this specification.

H. MONFORD SMITH.
